(57) **CLAIM**

The ornamental design for a reading pillow with head rest, as shown and described.

DESCRIPTION

FIG. 1 is a perspective view of a reading pillow with head rest showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of FIG. 1 showing the headrest components separated, creating an alternate configuration of use.

The broken lines throughout the drawing figures depict portions of the reading pillow with head rest that form no part of the claimed design.
